A. DRUMMOND,

DOOR CATCH.

APPLICATION FILED OCT. 12, 1916.

Patented Apr. 13, 1920.

FIG. 1.

FIG. 3.

INVENTOR:
ALBERT DRUMMOND

Hazard, Berry & Miller
ATTORNEYS

UNITED STATES PATENT OFFICE.

ALBERT DRUMMOND, OF LOS ANGELES, CALIFORNIA.

DOOR-CATCH.

1,336,897.

Specification of Letters Patent. Patented Apr. 13, 1920.

Application filed October 12, 1916. Serial No. 125,306.

To all whom it may concern:

Be it known that I, ALBERT DRUMMOND, a citizen of the United States, residing at Los Angeles, in the county of Los Angeles and 5 State of California, have invented new and useful Improvements in Door-Catches, of which the following is a specification.

My object is to improve the details of a door catch, and my invention consists in the 10 novel features herein shown, described and claimed.

Figure 1 is a view in elevation and section illustrating the door catch as applied for use in connection with a door frame and a 15 door.

Fig. 2 is a view in plan, elevation and section taken on line 2—2 of Fig. 1 and further illustrates the door catch in its applied position and with its parts engaged.

Fig. 3 is a view in vertical section as seen on the line 3—3 of Fig. 1 and as illustrating the manner in which the resilient locking fingers engage and conform to the movable member.

Referring more particularly to the drawings, 10 indicates the frame of the doorway within which a door 11 is adapted to swing upon suitable vertical hinges. The door indicated in the drawings is provided with a screen 12, although it is evident that other than screen doors may be satisfactorily fitted with this catch. Mounted upon the cross rail 14 at the upper edge of the door is an outwardly extending catch member 15 which is suitably secured by its base plate 16 to the frame and is formed with a horizontal stud 17 adapted to be engaged by, and disengaged from a catch member 18. The base plate 16 and the stud 17 are formed 25 integral and the base plate serves as an attaching plate for securing the stud rigidly in position upon the door. The stud 17 is formed with a conical end portion 19 back of which is an annular bead 20. This bead 30 is adapted to be engaged by the arcuate recesses 21 of oppositely disposed spring fingers 22 which are formed integral with a mounting plate 23 and which comprises the catch member 18. Reference being had to Fig. 3 of the drawings, it will be seen that 35 the recess portions of the fingers are arcuate in cross section to conform to the circu-

lar periphery of the bead 20 thus holding the stud 17 in a substantial manner when in engagement therewith.

55

The operation of the catch is as follows: Assuming that the door is locked as illustrated in Fig. 1 of the drawing, it will be evident that by pressing against the door as indicated by the arrow —a—, the stud 17 60 will be withdrawn from between the spring fingers 22 and will thus permit the door to swing open. In forcing the door open, the spring fingers must be forced apart to permit them to pass clear of the annular bead 65 20 upon the stud and the fingers will thereafter, due to their resiliency, close together. This position will be maintained by the fingers until the door is returned to its closed position, at which time the conical end 70 19 of the stud 17 will force its way between the outturned ends of the fingers and will cause the fingers to open for the reception of the annular bead 20 which will become seated within the recesses formed upon the 75 fingers. When in this position, the door will again be held against accidental opening.

It will thus be seen that the door catch here provided is of simple construction and 80 will operate in a positive manner to hold a door in, and release it from its closed position.

I claim:

1. A door catch comprising a base plate 85 adapted to be secured to the face of a door, a stud extending from the base plate at right angles; the stud having a conical end portion and an annular bead back of the end portion; a mounting plate adapted to be secured to the face of a door frame, and oppositely disposed arcuate spring fingers extending from the mounting plate and adapted to engage and yieldingly hold the bead; the outer ends of the spring fingers 90 being flared apart to receive the conical end, so that the bead will snap in and out between the fingers.

2. A door catch including a base plate adapted to be secured to the face of a door; a stud extending from said base plate at right angles thereto, a conical point at the forward end of said stud, an annular bead formed on said stud at the base of said coni-

cal point, a mounting plate adapted to be secured to the face of a door frame, oppositely disposed spring fingers arcuate in cross section extending from said mounting plate and shaped to fit firmly upon said bead and engage the rear face of said bead to hold the door firmly but yieldingly

closed, the outer ends of said spring fingers being curved and flared apart to receive said conical point and so that said fingers 10 will spring over said bead.

In testimony whereof I have signed my name to this specification.

ALBERT DRUMMOND.
